US00D986916S

(12) **United States Design Patent** (10) **Patent No.:** **US D986,916 S**
(45) **Date of Patent:** **** May 23, 2023**

(54) **DISPLAY SCREEN WITH A GRAPHICAL USER INTERFACE**

(71) Applicant: **Cameron International Corporation**, Houston, TX (US)

(72) Inventors: **Torstein Soerhaug**, Bergen (NO); **Carsten Falck Russenes**, Bergen (NO); **Knut Helge Rygg**, Bergen (NO); **Rajesh Kumar Bade**, Houston, TX (US)

(73) Assignee: **Schlumberger Technology Corporation**, Sugar Land, TX (US)

(**) Term: **15 Years**

(21) Appl. No.: **29/644,796**

(22) Filed: **Apr. 20, 2018**

(51) LOC (14) Cl. **14-04**

(52) U.S. Cl. **USPC** **D14/486**

CLAIM

The ornamental design for a display screen with a graphical user interface, as shown and described.

DESCRIPTION

FIG. 1 is a front view of a first embodiment of a display screen with a graphical user interface;

FIG. 2 is a front view of a second embodiment thereof; and, FIG. 3 is a front view of a third embodiment thereof.

The broken lines illustrate a display screen and form no part of the claimed design. The broken lines illustrate portions of the graphical user interface and form no part of the claimed design.

1 Claim, 3 Drawing Sheets
